SEAL CONFIGURATION FOR FOLDING
PARTITION

Guy J. Sanders, Severna Park, Md., assignor to Koppers Company, Inc., a corporation of Delaware
Filed June 19, 1963, Ser. No. 289,121
6 Claims. (Cl. 160—40)

This invention relates to soundproof folding partitions and, more particularly, to the prevention of sound leakage around the periphery of the panels comprising the folding partition.

In the ballrooms of hotels, in dining rooms and in other such areas, folding partitions are commonly used to provide means for readily subdividing a large room into smaller areas in a manner permitting the smaller areas to be just as readily re-converted to the large room by folding the plurality of hinged panel sections into stored position.

Unfortunately, in those situations in which it is desirable to effectively reduce sound transmission between areas which have been separated temporarily by the interposition of a movable partition, one of the difficult problems confronting designers has been that of securing adequate acoustical sealing between the partition in its extended position and the surfaces adjacent thereto. Although a partition may be composed of individual panels having a moderate or even a high degree of sound transmission loss, such performance is readily comprised in the event of inadequate sealing allowing even small cracks to remain between the outer edges of the partition and the room surfaces adjacent thereto forming a frame about such extended partition.

These small cracks are extremely important to the acoustical integrity of the structure because a good acoustical seal cannot be obtained as long as such gaps are present in the structure. This fact is referred to in many acoustical texts, for example, in Chapter 20 (pages 20-13 and 20-14) of the "Handbook of Noise Control" edited by Cyril N. Harris, published by McGraw-Hill (copyright 1957). The chapter of which the aforementioned pages form a part was written by Richard K. Cook and Peter Chrzanowski of the National Bureau of Standards. The authors describe the propensity of small slits to short circuit an otherwise good sealing system. To quote from the opening paragraph of "Small Openings" on page 20-13, "The sound insulation of a well-designed wall, for example, one having a transmission loss of 50 db, can be vitiated easily by an opening in it even though the opening may be so small as to escape notice."

The problem is particularly severe along the base of the partition, because of the separation of the partition into individual panels, which are reoriented relative to each other during the extension and folding of the partition, since the conventional foot gasket is a solid block of rubber or similar resilient material extending from end to end along the bottom of each separate panel, thereby at best providing a discontinuous seal with periodic gaps between the individual lengths of foot gasket.

Further, in order to permit ready transport of the door panels from the extended to the folded position and vice versa, clearance must be provided between the underside of the conventional foot gasket and the floor. When the door has been moved to its extended position wherein a seal is required along the underside thereof, means must be provided to bias downwardly at least that portion of each panel housing the foot gasket until the gasket is compressed against the floor.

Consequently, it is an object of this invention to provide a truly continuous seal along the underside of a folding partition.

Another object of this invention is to provide an inflat-

able seal for the periphery of a folding partition which is completely protectively housed during the transport of the folding partition and during the folding or extending thereof and which seal upon the admission of air pressure to the interior thereof is made to protrude from its protective housing to seal against the surface in juxtaposition therewith without requiring further movement of the door panels or of any other portion of the door structure to complete the sealing action.

10 It is a further object of this invention to provide a continuous seal actuatable to sealing position as a single unit along the lower and leading edge of a sectional folding wall.

These objects and others are attained with this invention 15 by employing a collapsible seal configuration of molded resilient material, such as rubber, neoprene or silicone (with or without fiber reinforcement) extending the full length of the lower edge of the folding partition bridging the gaps between adjacent interconnected panels comprising the partition and, if desired, continuing vertically 20 upward along the extent of the height of the leading edge of the folding partition. The particular seal configuration to be employed depends on (a) the area of sealing surface required, (b) the facility with which the outwardly directed portion of the seal may be moved out of storage position or returned completely within its storage 25 recess and (c) the capacity of the seal to adjust to the stacking of the several panels as the door is folded and each panel is backed face-to-face with the panel or panels 30 with which it is interconnected.

The exact nature of this invention as well as other objects and advantages thereof will be readily apparent from consideration of the following specification relating to the annexed drawing in which:

35 FIG. 1 is an isometric view of a soundproof partition in a partially extended position,

FIG. 2 is a sectional view taken on line 2—2 of FIG. 1 showing the relative positions of the leading edge of the door panel, side jamb and the preferred embodiment of this invention disposed in the unsealed position,

FIG. 2a is a sectional view taken on line 2—2 of FIG. 1 showing the relative positions of the door panel, side jamb and the preferred embodiment of this invention disposed in sealing position,

FIG. 3 is a sectional view taken on line 3—3 of FIG. 1 showing the relative positions of the lower edge of any door panel, the floor and the preferred embodiment of this invention disposed in the unsealed position,

FIG. 3a is a sectional view taken on line 3—3 of FIG. 1 showing the interrelationship of the lower edge of any door panel, the floor and the preferred embodiment of this invention disposed in sealing position,

FIG. 4 is a sectional view taken on line 4—4 of FIG. 1 a short distance above the top side of the preferred seal 55 construction showing the disposition of the length of the bottom-edge seal when the panels are arranged in stacked position,

FIG. 5 is a section taken on line 5—5 of FIG. 4 showing the lateral accordion-like folding of the preferred seal construction which occurs at this position as the seal reorients itself during movement of the door panels to the stacked position,

FIG. 6 is a sectional view taken on line 6—6 of FIG. 4 similar to FIG. 5 in that the lateral accordion-like folding 60 of the seal prevailing at this position is shown,

FIG. 7 is an elevational view partially cut away showing the construction at the bottom of the door jamb to provide optimum sealing at the lower corner of the leading edge of the folding partition in the optional sealing arrangement wherein the seal configuration extends vertically upward along the leading edge as well as along the full length of the lower edge of the folding partition,

FIG. 8 is a section taken on line 3—3 of FIG. 1 showing the relative positions of the lower edge of any panel, the floor and a second embodiment of a seal configuration suitable in the practice of this invention wherein solid lines represent the position assumed by the seal in the uninflated state and dotted lines represent the configuration assumed by the seal inflated to the sealing position,

FIG. 9 is a sectional view taken on line 5—5 of FIG. 4 showing the configuration assumed by the second embodiment of the sealing element after self-reorientation thereof by the lateral accordion-like folding occasioned during movement of the door panels to the stacked position and

FIG. 10 is a line diagram showing a pneumatic arrangement for actuating the seal.

Referring now to the drawings, wherein like reference characters designate like or corresponding parts throughout the several views, there is shown in FIG. 1 a folding partition 11 comprising a plurality of hinge-interconnected panel sections 12 some of which are shown in the stacked or storage position and others of which are shown in the partially or completely extended position.

Every other panel 12 depends from the overhead track system 13 (shown schematically) by means of roller trucks (not shown). Those panels arranged between the alternate depending truck-supported panels 12 are supported by the depending panels by means of hinges 14, which connect adjoining panels. At alternate joints, hinges 14 are placed on opposite sides of the folding partition 11. With this arrangement it is but a simple matter to reorient the panels 12 in a direction parallel to the longitudinal axis of the overhead track system 13 causing the several panels 12 to fold or unfold relative to each other depending upon the direction of movement.

In the particular arrangement disclosed by way of example, inflatable seal 16 is shown disposed in storage recess 17, which is in the shape of a box channel extends along the length of the leading and lower edges of the folding partition 11. The approximate configuration assumed by seal 16 when deflated and disposed in storage recess 17 in any panel 12 arranged in its extended position is shown in FIGS. 2 and 3. The configuration assumed by seal 16 when in the inflated state and moved into sealing position is approximated in FIGS. 2a and 3a.

Seal 16 is formed of molded resilient material such as rubber, neoprene or silicone in the deflated configuration thereof shown in FIGS. 2 and 3. If required, additional strengthening of the seal construction may be supplied by the use of fiber reinforcement. The several integrated sections comprising seal 16 are the pair of side flanges 18, 19 adjacent the side walls of recess 17 and the pair of spaced-apart walls 21, 22. For convenience, wall 21 will be referred to as the inner wall and wall 22 the outer or sealing wall. A portion near each end of each of walls 21 and 22 is formed of a relatively thick section of material rendering these portions of the walls less susceptible to flexure or deformation. The thicker, more rigid portions of wall 21 are identified by the numerals 23, 24 and the thicker portions of wall 22 are identified by the numerals 26, 27.

Disposed between the thickened, less flexible portions 23, 24 and 26, 27 of the walls 21 and 22 respectively are the inner, more flexible diaphragm sections 28, 29 respectively. These diaphragm sections 28, 29 are arranged in spaced, substantially parallel arrangement defining a space 31 extending the length of seal 16. Provision for introducing air under pressure into space 31 to effect inflation of seal 16 will be described in detail below.

When pressurized air is introduced into seal 16, walls 21 and 22 are repositioned relative to each other under the influence of the internal pressure exerted within space 31. Thus, as is shown in FIGS. 2a and 3a, wall 21 will be moved inwardly of recess 17 until diaphragm section 28 presses with the width, or substantially all the width, thereof against rear wall 32 of recess 17. Simultaneously

therewith wall 22 will be forced from its initial position, wherein it is entirely within recess 17, until it protrudes past lips 33 of storage recess 17. As sufficient air under pressure is introduced into the interior of seal 16, wall 22 will be biased outwardly until it spans the gap 34 between lips 33 and the face 36 of door jamb 37 and also spans the gap 38 between lips 33 and the surface of floor 39.

Thus, after panels 12 of folding partition 11 have been moved to their extended position to substantially close the opening for which partition 11 has been fitted, air under pressure may be admitted to space 31 to inflate seal 16 thereby causing the configuration thereof to change in the manner described above to effect a positive seal between door panels 12 and each of floor 39 and door jamb 37.

Since space 31 extends through substantially the entire length of seal 16, only one air inlet 41 (FIG. 10) need be furnished. This air inlet 41 will be advantageously located in the portion of seal 16 in that panel 12 closest to the abutment against which the folding partition 11 is stocked. By locating air inlet 41 in this end panel, tube 42 which is connected to air inlet 41 can be disposed in this end panel 12 extending upward through the means employed to depend this end panel 12 from the overhead track system 13 and thence into a wall housing (not shown) to connect with a source of pressurized fluid 43. Sufficient extra length of flexible tube 42 must be permitted to compensate for the movement of the end panel 12 during the extension and folding of partition 11.

Air inlet 41 may be placed into or out of communication with source 43 by means of a conventional solenoid-actuated valve 44 located in the length of tube 42. A second solenoid valve 46 may be disposed in tube 42 between valve 44 and air inlet 41 either to place solenoid valve 44 into communication air inlet 41 or to place air inlet 41 in communication with the atmosphere.

Thus, with solenoid valves 44 and 46 properly positioned, air under pressure will pass from source 43 through tube 42 via valves 44 and 46 into space 31 to inflate seal 16. Once sealing wall 22 has been biased into sealing position the pressure in space 31 will rise sharply actuating a pressure switch 47, which switch will in turn reset solenoid valve 44 to cut off the passage of pressurized air to space 31 while retaining the desired sealing pressure already therein.

When folding partition 11 is to be withdrawn from its extended position and moved into stacked position, it is simply necessary to actuate solenoid valve 46 as by a conventional control button (not shown) at some accessible position whereby valve 46 will be positioned so as to vent space 31 to the atmosphere. As air leaves space 31 the several portions of walls 21 and 22 retract to the deflated configuration shown in FIGS. 2 and 3, this being the unstressed position of the elements comprising seal 16.

The rigid portions 23, 24, 26 and 27 of these walls by their very nature further urge the return of diaphragm sections 28 and 29 to the deflated configuration wherein, preferably, no portion of seal 16 protrudes from storage recess 17 and air is effectually urged out of space 31.

When seal 16 has returned to its deflated condition and gap 38 is provided giving the necessary clearance between the underside of partition 11 and floor 42 to enable unencumbered movement of panel sections 12, the panels 12 may be moved to the stacked position manually or by mechanical actuation.

As the panels 12 are repositioned to the closely stacked vis-a-vis position, the continuous flexible seal 16 in its deflated condition, which extends along the lower edge of partition 11, adjusts to this new set of conditions by assuming the position relative to the side walls of recess 17, wherein it is shown in FIG. 4. Therein it may be seen that seal 16 in traversing from one end of any given panel 12 to the other end thereof extends diagonally along that length of recess 17 embodied in that particular panel. Seal 16 is continuous from panel to panel and

this seal must fold around hinges 14 at each end of panels 12. However, the distance along the centerline of recess 17 from the top of the leading edge of partition 11, down the full height thereof and along the length of the lower edge of partition 11 in its extended position is less than the distance along the centerline of recess 17 similarly measured with the panels 12 in stacked position and allowing for connecting arcs at the ends of the stacked panels to make this centerline continuous along the lower edge thereof. Thus, if seal 16 were to be formed in a configuration retaining a constant, or substantially constant, width the centerline of such a seal would coincide by and large with the two positions of the centerline of recess 17 described above, first, in the extended position and second, in the stacked position. Since any continuous seal installed along the underside of partition 11 would have to be restricted in the extent of its movement lengthwise relative to recess 17, a seal with the aforementioned limitation would soon rupture when partition 11 is extended and folded repeatedly because of the taxing degree of elongation and deformation imposed thereupon.

With the novel configuration shown in FIGS. 2 and 3, however, the problem of rupture has been obviated as is best illustrated in FIGS. 5 and 6, this seal construction is provided with the unique ability to move laterally within recess 17 folding in an accordion-like fashion into a compact width of less than half the width of recess 17. Coupled with this facility of seal 16 to fold and extend in the horizontal direction (as well as to fold and expand out of and into recess 17) has been the necessity of recognizing the fact that seal 16 can be housed in recess 17 provided with lips 33 without attaching seal 16 in the individual panels yet without encountering the problem of dropout of seal 16 from recess 17. As has been stated above, all that is necessary is to restrain the extreme far ends of continuous seal 16, preferably in a resilient manner, and as the panels 12 are folded and tension begins to be exerted thereon, seal 16 folds laterally to one side or the other diminishing its width by over 50% and extending diagonally of panels 12 as shown in FIG. 4 in the shortest zizzag path from the lower corner at the leading edge of the foremost panel to the lower corner at the trailing edge of the rearmost panel when panels 12 are finally arranged in the stacked position. Because of the reduced width of the laterally folded seal 16, the turning radius required around each hinge 14 is minimized as well.

As the result of the invention of these novel aspects, relatively little stretching, not over 20%, is imposed upon seal 16 during stacking and while in the stacked position, an amount which is easily accommodated by ordinary resilient materials. Rupture of seals so designed is reduced to a minor maintenance problem and, in the event replacement of the seal should be required, it is but a simple matter to thread the replacement seal along the length of recess 17 without major disassembly of the panel arrangement.

In order to assure positive sealing contact in the region where continuous seal 16 extends around a corner in the plane of panel 12 as in the present illustrative construction, an arrangement such as is shown in FIG. 7 may be employed. The box channel forming recess 17 is curved on a moderately short smooth radius and thereby seal 16 is housed on a curve in this region. As seal 16 is inflated, the wall 22 exits from recess 17 and meets the curved block 48 producing an airtight joint therewith completing the airtight joint formed thereby along the lower and leading edges of partition 11. Block 48 can be made relatively small so as to be inconspicuous and may either be nailed or glued in place against jamb 37 and floor 39 or may be formed of solid rubber and glued to the seal 16 whereby block 48 will be retracted with seal 16 upon deflation thereof.

A second embodiment of seal configuration is shown

75

in FIGS. 8 and 9. The same shape recess 17 is employed being provided within box channel 51 and seal 52 housed therein performs substantially in the same manner as seal 16. FIG. 8 shows the displacement of seal 52 from its retracted position entirely within recess 17 (solid lines) outwardly in the plane of the panel 12 upon inflation (dotted lines). As in the case of seal 16, seal 52 is not attached to the several panels 12 intermediate the far ends of seal 52 and the configuration of seal 52 is such that when the seal is folded around hinges 14 in the stacking operation and tension begins to be exerted along the length of seal 52, the seal folds laterally in accordion-like pleats to one side or the other of recess 17 (FIG. 9) thereby greatly reducing the degree of deformation imposed upon the seal.

It should be understood that the continuous seal has been disclosed herein by way of example as extending up the leading edge of the folding partition, but that the use of the continuous seal may, if desired, be restricted to the lower edge of the folding panels wherein the benefits of this novel development are most completely employed.

Further, folding partitions the individual panels of which fold up into or emerge from suspended ceiling construction on a suitable track construction have been proposed and this invention is equally applicable thereto. In such installations, of course, the hinge-connection is horizontally, rather than vertically, disposed, but problem of sealing of peripheral cracks along the sides and lower edge remains the same.

Obviously modifications and variations of this invention as disclosed are possible in the light of the teachings provided herein. It is thus to be understood, that within the scope of the appended claims, the invention may be practiced otherwise than as specifically illustrated.

What is claimed is:

1. A folding partition comprising a plurality of sound-proof panels adapted to be supported on a horizontal track assembly, hinges connecting said panels such that the plurality of panels can selectively be extended along said track assembly so that said panels extend parallel to the track assembly to form a substantially uninterrupted barrier to close an opening with the surfaces of the panels approximating a single plane surface and be folded along the hinge connections so that the panels are normal to the track assembly to remove the panels from the opening, a recess extending along the lower edge of each of said panels, a continuous inflatable resilient sealing means spanning at least the length of said barrier and housed in said recess, said sealing means having a portion capable of being expanded out of said recess in the inflated state and being autogenously collapsible laterally within said recess in the deflated state and means for expanding said sealing means out of said recess.

2. The apparatus of claim 1 wherein said sealing means can be folded laterally within the recess to an overall width of about 50% of the width of said sealing means in the substantially unstressed state.

3. The apparatus of claim 1 wherein in a cross-section thereof in a plane perpendicular to the longitudinal axis of said seal, each of the walls and the space defined thereby appears substantially M-shaped in cross-section.

4. The apparatus of claim 1 wherein enlargements in the cross-section of each wall occur at the high points of each M to facilitate the autogenous return of the seal to the uninflated state.

5. The apparatus of claim 1 wherein in a cross-section thereof in a plane perpendicular to the longitudinal axis of said seal, each of the walls and the space defined thereby appears substantially W-shaped in cross-section.

6. The apparatus of claim 1 wherein enlargements in the cross-section of each wall occur at the points of changes in direction of the several portions of each W-shaped wall.
